UNITED STATES PATENT OFFICE.

EDWIN W. MEADER, OF LISBON, MAINE.

INHALER.

SPECIFICATION forming part of Letters Patent No. 357,617, dated February 15, 1887.

Application filed April 17, 1886. Serial No. 199,272. (No model.)

To all whom it may concern:

Be it known that I, EDWIN W. MEADER, a citizen of the United States, residing at Lisbon, in the county of Androscoggin and State 5 of Maine, have invented a new and useful Inhaler for Fluid Anæsthetics, of which the following is a specification.

In administering ether it is usually desirable to bring about insensibility as quickly as 10 possible, and in order to attain this end it is necessary that all the air which the patient breathes should be thoroughly saturated with ether vapor.

In the apparatus for administering ether 15 now in use this saturation of the air with ether vapor is more or less imperfect and uncertain.

A principal object of my invention is to provide a device which shall be in this respect more efficient and reliable.

20 Further objects of my invention are, first, to make as small as possible the suffocation of the patient, which is caused by preventing him from breathing a normal amount of air, or by compelling him to re-breathe his exhaled 25 breath; second, to save the ether which is unnecessarily consumed in present practice.

In carrying out my invention I provide for covering the patient's nose and mouth a piece having the form of a hollow cone. I do not 30 confine myself to a particular construction of this piece, but employ by preference such of the forms now in use as most completely shut out the outside air. The outer end of this cone is connected with the mixing-receptacle, 35 which forms a leading feature of my invention, by a tube, and in a part of this tube are preferably placed the valves which permit the breath of the patient to pass out of the apparatus and the air charged with ether to pass in.

40 In the accompanying drawings, Figure 1 shows a sectional elevation of a complete inhaler. Fig. 2 shows that part of the apparatus in which the ether and air are mixed separated from the other parts and covered with 45 its cap. Figs. 3, 4, and 5 show alternative positions of the connecting-tube.

In these drawings, A is the outer case of the mixing-receptacle. B is a partition dividing this receptacle into two compartments. For

greater convenience of construction, A and B 50 are preferably made of cylindrical form.

P, P', and P" are apertures through the lower part of B, which permit the ether to flow freely from one compartment to the other. These apertures are most conveniently made in the 55 manner shown in Fig. 1, where the partition B is attached to the bottom of the outer case, A, by short projections, and is separated from it elsewhere by a narrow slit.

S is a piece of sponge or other porous material in the interior compartment. 60

R is the cover of the inner compartment, B. T is a tube connecting B with the mouth-piece M.

J J' are joints in the tube T. 65
I is the inlet-valve; O, the outlet-valve.

C, Fig. 2, is the cover of the outer case, A. In using my invention I remove the cover C, Fig. 2, and place in the vessel A a sufficient amount of ether. I next put in place the 70 cover R and the parts shown in connection in Fig. 1. The instrument is then ready for use. As it is desirable to keep the receptacle A nearly horizontal, a certain amount of flexibility is necessary in the tube T. This I prefer to attain by introducing the joints J J', 75 which permit the mouth-piece to be adjusted to the face of the patient in either a sitting or a recumbent position. As the requirements of different departments of surgical and dental practice are somewhat different, an inhaler which had the most convenient form for use in a particular department would have a particular place of attachment for the connecting-pipe and the mixing-receptacle. The only essential feature is that the tube T should connect the upper part of the compartment B 80 with the valves and mouth-piece.

In the diagram Fig. 3 the tube is shown entering at right angles through the walls of 90 both the outer and the inner compartments. In Fig. 4 it enters at an acute angle. In Fig. 5 it passes directly upward through the bottom.

As will be seen from the drawings, Fig. 1, when the mouth-piece M is in close contact 95 with the face all the air breathed by the patient must first bubble up through the ether in the receptacle A and afterward pass over

the surface of the saturated sponge. It thus becomes thoroughly charged with ether vapor. When the etherization of the patient is accomplished, the tube T and its attachments are disconnected from the inner compartment and the tight-fitting cover C is placed upon the whole receptacle, as shown in Fig. 2.

When the tube T passes through the side, as shown in Figs. 3 and 4, the cover C will require a deeper rim than shown in Fig. 2.

Having fully described my invention, what I desire to claim and secure by Letters Patent is—

In an inhaler, the combination of a mouth-piece, inlet and outlet valves, a mixing-receptacle divided into two compartments which are connected at the bottom, and of which one is open at top to the outside air, while the other is closed at top, and a tube connecting said closed compartment with the inlet-valve, all substantially as specified. 15 20

EDWIN W. MEADER.
